SNAP-ON DUSTGUARD

Donald D. Bryant, Huntington, W. Va.

Application December 26, 1950, Serial No. 202,650

5 Claims. (Cl. 286—6)

1

This invention is a novel snap-on dustguard for journal box housings or the like, particularly adapted for use in freight car, passenger car, and locomotive trucks and tender journals, but may be used in any other desired places.

The present invention is an improvement on the dustguards shown in my U. S. Letters Patents No. 2,429,867 dated October 28, 1947, and No. 2,391,121 dated December 18, 1945.

The axles of freight and passenger cars, as well as locomotive trucks and tenders, are journaled in journal box housings, and it is required by the A. A. R. to provide dustguards in said journal boxes in order to keep dust, dirt, water, moisture and other foreign or abrasive material from entering the end of the journal box housing along or around the axle. Failure to provide such dustguards would leave an opening through which such dust, dirt, grit, etc., picked up by the rapid movement of the train could enter, the same resulting in undue wear or abrasion between movable parts, or scoring of the highly polished or finished surface of the journals, or causing waste or packing thread grabs, or causing rusting or spotting of the burnished journal bearing seats often resulting in hot boxes causing derailment, destruction of equipment, train delays, or loss of human life to train crews as well as the travelling public.

The dustguards now in general use, required by the A. A. R., are held in place in a cavity pocket cast or formed in the journal box housing, and the dustguard is usually formed of rigid plywood or fibre which fits into the cavity pocket, the fibre or plywood sections of the dustguard being riveted or stapled together. The present dustguards are of little or no protection for the purpose for which same are intended, since the same are not contractible so as to fit snugly around the axle, nor are same adjustable for wear. Moreover same, being rigid, are therefore liable to breakage since their rigidity allows no flexibility. Such dustguards cannot be removed without removing the truck from the car and disengaging the entire truck assembly, and therefore the usual dustguards, above described, are damaged or destroyed when the car is jacked-up to remove or renew the journal brass, which brass must be renewed when damaged, worn, or when for any reason a failure therein occurs. The brass is renewable without shopping the car for repair, but the dustguard, which has been so damaged by jacking-up the car to remove the brass, no longer serves as a protection in its broken condition and thus becomes a source of danger or liability.

2

With respect to the present dustguards, no means are provided for removing or replacing same without shopping the car for heavy duty repair; and thus from a servicing standpoint the present dustguard is impractical, and is inefficient since it does not contain self-adjusting features. Heretofore it has been necessary to scrap the dustguard unit as a whole, no part being interchangeable or salvaged.

10 Due to the above conditions, a serious need has arisen for some improvement, which would give the desired necessary protection, would eliminate the hazard to the axles, and their appurtenances, would prevent hotboxes, protect equipment, 15 would save train delays and derailments and serious injuries to the train crews and the travelling public, and which would save needless expenditures for parts and labor.

20 The principal object of my invention is to provide a snap-on rack containing dustguard band sectors, adapted to fit into the usual cavity pocket cast in the journal box housing, which rack will not be damaged by jacking-up the car to remove the journal brass as the brass may be readily removed after removing the rack from the cavity.

25 A further object of the invention is to provide a dustguard as above described which may be entered bodily into and removed through the opening at the top of the dustguard cavity of the journal box, said dustguard carrying band sectors whereby as the dustguard is forced down into the cavity the sectors will be guided to encircle the journal, the dustguard band being held closely in place around the axle journal to compensate for wear of the dustguard band sector.

30 A further object of the invention is to provide a snap-on dustguard of the above type which may be removed at any time without the use of extraneous tools, its ready accessibility making it convenient for removal at any place or time 35 by merely pulling same out of the dustguard cavity and replacing it again, its entire removal and replacement requiring only a few minutes time to complete.

35 Other minor objects of the invention will be hereinafter set forth.

40 I will explain the invention with reference to the accompanying drawings, which illustrate one practical embodiment thereof, to enable others familiar with the art to adopt and use the same; and will summarize in the claims, the novel features of construction, and novel combinations of parts, for which protection is desired.

45 In said drawings:

50 Fig. 1 is a transverse section through the dustguard cavity of a journal box housing equipped

with my improved snap-on dustguard and showing the dustguard inserted into the cavity pocket and encircling the axle journal.

Fig. 2 is a horizontal section on the line 2—2, Fig. 1.

Fig. 3 is a plan view of the dustguard detached, when removed from the cavity pocket.

Fig. 4 is a plan view of one of the band sectors, detached.

Fig. 5 is a top plan view of the sector shown in Fig. 4.

Fig. 6 is an end view of the sector, shown in Fig. 4.

Fig. 7 is a reduced plan view of the snap spring.

Fig. 8 is a side elevation of the snap spring shown in Fig. 7.

As shown, the axle journal J, of the car truck or other equipment, is entered in the normal manner into the journal box containing the packing saturated with lubricant in the usual manner, the particular form of the journal box forming no part of my present invention. Such journal boxes are customarily provided at their inner ends with a dustguard cavity B' for the reception of the dustguard hereinbefore referred to.

In place of the usual dustguard formed of layers of plywood or fibre riveted or stapled together, I provide a snap-on dustguard of such size and dimension as to fit within the cavity B' which is ordinarily open at the top of the journal box same making a loose fit within the cavity, as shown more particularly in Figs. 1 and 2.

My novel snap-on dustguard comprises a cover plate 1 adapted to close the open upper end of the dustguard cavity B' in the journal box, said plate being of greater length than the width of the journal box, as shown in Fig. 1, leaving overhanging portions 1a at each end thereof. The central portion of the cover plate 1 is stamped so as to provide a centrally disposed upwardly extending portion 1b of substantially triangular shape, while the portions of the plate 1 adjacent the ends are depressed as at 1c, the bottom edges thereof forming substantial continuations of the upwardly extending tops of the extension 1b, as shown, and the outer ends of the depressions 1c forming shoulders 1d spaced from the inner faces of the side walls of the cavity B' to allow the cover plate 1 to shift laterally while extensions 1a still cover the opening in the journal box. When cover plate 1 shifts laterally, one or the other shoulder 1d will strike the side wall of the cavity and prevent the plates 11 and 3 (hereinafter referred to) from striking the side walls of the cavity and becoming damaged, said lateral shifting occurring generally during starting and stopping of the car, such motion jerking the axles laterally of the journal boxes. As the cover plate thus shifts and shoulder 1d contacts the side wall of the cavity, since the snap spring 13 (hereinafter referred to) is pivoted thereto, the dustguard may move freely with the lateral motion of the axle and cannot become damaged. However, the plate 1 may be readily removed from the journal box by merely gripping the extensions 1a and lifting same upwardly. Extending through the central upward extension 1b adjacent the center thereof are aligned openings 1e for the reception of a removable cotter pin 2 (Figs. 1 and 3) for the purpose hereinafter explained.

Adapted to be housed within dustguard cavity B', is a rack consisting of spaced metallic plates 3—3 which are of general rectangular shape, each having a semi-circular recess 3a in its lower

face of slightly larger radius than the exterior diameter or axle journal J, as indicated in Fig. 1, said semi-circular portion terminating opposite the horizontal axis of journal J, and having outwardly extending shoulders 3b. The sides of the plates 3 at opposite sides of journal J extend as at 3c below the horizontal axis of journal J and are spaced from the inner walls of the cavity B' of the journal box below the horizontal axis of journal J, as shown in Fig. 1.

Preferably the plates 3 are maintained separated by means of a central block 4 and side blocks 15 (Figs. 1 and 3) through which rivets 5 or the like are passed, the blocks 4 and 15 being of thickness less than the length of dustguard cavity B' of the journal box. Between the plates 3 extending around the arcuate portion 3a from shoulder 3b to shoulder 3b, is a felt or other packing 6 (Fig. 1), the same projecting beyond the semi-circular surface 3a and adapted to make a tight contact with the upper periphery of the axle journal J, when the rack is inserted into the cavity B' in position shown in Fig. 1.

In the parallel plates 3, extending from a point below the horizontal axis of journal J to a point adjacent the top periphery of the journal J, are arcuate slots 3d at each side of the journal J, the same having the same concentricity as the journal J. The lower ends 3c of the sides of the rack are open, and housed within the spaced lower ends 3c are sector shoes 7, shown more particularly in Figs. 4, 5 and 6, the same being of overall length to extend from points beyond the lower periphery of journal J to points above the horizontal axis of journal J when the dustguard is closed, as shown in Fig. 1.

In the inner periphery of each sector shoe 7 is a slot 7a in which is securely mounted a felt or other packing 8 (Figs. 1 and 3) adapted with the felt packing 6 of plates 3 to completely surround the journal J when the dustguard is in the position shown in Fig. 1.

Each sector shoe 7 is provided with a perforation 7b through which extends a pin 9 having flattened heads 9a at each end closely overlying the plates 3, the pins 9 being movable in the slots 3d so that the sector shoes 7 may move from positions within the rack 3, as shown in Fig. 3, into extended positions shown in Fig. 1 in which the sector shoes 7 embrace the lower periphery of journal J. Slots 3d are wider than the diameters of pins 9, so that under severe impact shock this would allow snap spring 13 to move sector shoes 7 laterally independently of plates 3—3. However, should sector shoes move laterally they would still maintain an unbroken seal around the axle because of the tongue extension of one sleeve which fits the groove of the other sector shoe. Cover plates 11 (Fig. 2) which are of the same shape as the plates 3 but which are not provided with any slots such as 3d are preferably provided on plates 3 so as to present a smooth exterior to the inner and outer faces of the rack. The flat heads of pins 9 slide between the plates 3 and 11. Plates 11 are applied to keep the dirt from entering slots 3d and to prevent pins 9 from coming in contact with the inside of the rough cast journal box, which might prevent the dustguard from being applied or removed.

As shown, the upper ends of the sector shoes 7 are slotted as at 7c, said slot crossing the holes 7b for the purpose hereinafter explained.

In order to actuate the sector shoes 7 by and with the upward or lowering movement of the

cover 1, an inverted U-shaped snap spring 13 is provided having one, two or more eyelets 13a at its upper end, through any one of which the cotter pin 2 may be passed so as to raise or lower the normal elevation of the cover 1 with respect to the journal J to suit discrepancies in the construction of the journal box, or more particularly the dustguard cavity B' of the journal box.

The legs of snap spring 13 are bowed downwardly, as shown, the same entering the upper end of the rack 3-3, and being provided on their lower ends with hooks 13b, as shown more particularly in Figs. 7 and 8, the said hooks surrounding the pins 9 carried by the sector shoes 7, and the lower ends of the legs of snap spring 13 being adapted to enter the slots 1c of the sector shoes 7 so that when the cover 1 is pulled upwardly to remove the rack 3-3 from the cavity B' of the journal box, the snap spring 13 will pull the sector shoes 7 from their normally closed positions shown in Fig. 1, in which they encircle the lower portion of journal J, into uppermost position shown in Fig. 3. The sector shoes 7 lies between the plates 3-3 of the rack, and when in the position shown in Fig. 3 clear the overall width of journal J, as indicated in Fig. 3, in which position the dustguard rack 3-3, including the cover 1, and snap spring 13 may be readily removed from the dustguard cavity B' without resorting to dismantling of the journal box, or to the use of any extraneous tools for causing separation of parts.

When the parts are thus raised, as shown in Fig. 3, it will be noted that leaf springs 14 mounted on blocks 15 at the upper corners of the rack 3-3 will engage the outer periphery of the sector shoes 7 and thereby serve as guides for the sector shoes 7 which with the slots 3d causes the shoes 7 to move in an arcuate path during the opening movement of the shoes 7 into the position shown in Fig. 3. The same springs 14, during closing movement of the shoes 7 into position shown in Fig. 1, when the cover 1 is being inserted down into the dustguard cavity B' will cause the sector shoes 7 to move in substantially the same arcuate path so as to close around the lower periphery of journal J. Springs 14 are preferably made long enough to engage the upper beveled ends of the sector shoes 7 when the latter are in closed position, as shown in Fig. 1, to maintain the lower ends of the sector shoes 7 in locking engagement around the lower periphery of journal J. Springs 14, when positioned as in Fig. 1, lock the upper ends of sector shoes 7 in downward position, thus maintaining the pins 9 at the lower ends of slots 3d whereby the sector shoes 7-7 will maintain an unbroken, self adjusting, swingable, flexible and movable dustguard band around the lower half of the axle.

In order to form a dustproof engagement, the lower end of one sector shoe 7 is reduced in thickness to form a tongue, and is adapted to enter a correspondingly shaped slot in the lower end of the other sector shoe 7, so that when the sectors are in closed position shown in Fig. 1 a complete unbroken ring of felt or other packing 6-8 will be formed around the journal J.

In Fig. 5 the slotted lower end of one of the sector shoes 7 is indicated by the numeral 1x, the same being adapted to receive the correspondingly shaped tongue at the lower end of the other sector shoe.

My novel dustguard constructed as above de-

scribed forms a ready snap-on dustguard which does not require that the axle be removed from the journal box in order to apply or remove the dustguard. All that is necessary to do is to manually depress the rack 3-3 into the dustguard cavity while in the opened position shown in Fig. 3 and push the cover 1 down into position shown in Fig. 1 so as to close the top of the dustguard cavity, such movement causing the sector shoes 7 to embrace and interlock under the lower periphery of journal J due to the tension of the snap spring 13 and to the closing action of the shoe actuating parts. The snap spring 13 holds sector shoes 7 closely around the axle at all times by its snap action. This closing or snap action urges the sector shoes tightly around the lower section of the journal and allows the tongue on one shoe to fit in the groove in the end of the other shoe, thus allowing the dustguard to be self-adjusting to fit under-sized axles and compensate for natural wear. The dustguard, when thus positioned, owing to the flexibility of the snap spring 13, is free to move up or down or laterally of the dustguard cavity B' by and with the movement of the axle journal J in said cavity, and thus, in all operating positions of the axle in the journal box, the dustguard will form a perfect shield around the journal. Moreover, the journal J may move axially of the journal box since the dustguard rack is of less thickness than the length of cavity B'.

The use of my dustguard, therefore, effects a tremendous saving in time and labor in inserting, servicing, or replacing dustguards, in that it is not necessary to disassemble the axle from the journal box, my dustguard being, as stated above, a ready snap-on dustguard insertable or removable at will by merely inserting or removing the dustguard from the open end of the cavity B', without the aid or use of any extraneous tools whatsoever.

I do not limit my invention to the exact form shown in the drawings, for obviously changes may be made therein within the scope of the claims.

I claim:

1. A snap-on dustguard seal for a journal box or the like, having a cavity pocket thereacross provided with a bore for an axle journal, the top of said pocket being open; a removable closure for the said pocket; a rack within the pocket including spaced plates extending transversely of said journal and having opposed semi-circular recesses in their lower edges of slightly larger radius than the journal and receiving the upper half of the journal; a packing between the plate and journal contacting the upper half of said journal; said rack having upwardly extending arcuate slots therein at opposite sides of the journal; arcuate sector shoes disposed between the plates having hinge pins slidably engaging the slots and adapted in lowered position to close around the lower half of the journal; packing carried by the shoes adapted in lowered position of the shoes to contact the lower half of the journal; said shoes when raised being withdrawn within the said rack to clear the said journal; and means yieldably connecting the closure and the shoe pins outside of the arcuate path of said pins, whereby as the closure is raised the shoes will be withdrawn, and whereby as the closure is lowered the shoes will be lowered.

2. In a seal as set forth in claim 1, said yieldable means comprising a snap spring having legs passing down through the top of the rack and

having their lower ends respectively engaging the pins of the shoes between the plates of the rack, said snap spring being of resilient material and having a vertically disposed series of eyes at its center selectively receiving a pin transfixing the said closure.

3. In combination with a seal as set forth in claim 1, leaf springs outside the arcuate path of the pins carried by the rack engaging the upper outer edge portions of the shoes when the latter are withdrawn, said springs engaging downwardly and outwardly beveled upper ends of the shoes when the latter are in lowered position to maintain the shoes closed around the lower half of the axle journal.

4. In combination with a seal as set forth in claim 1, said pins having flattened heads engaging the outer faces of the rack plates; and face plates covering the said rack plates and the slots and pin heads.

5. In a seal as set forth in claim 1, said yield-

able means comprising an inverted U-shaped snap spring having legs passing down through the top of the rack, the lower ends of the legs entering slots in the upper outer portions of the shoes, said pins crossing said slots; and said legs having eyes at their lower ends respectively receiving the pins of the shoes between the plates of the rack, said snap spring exerting a tension on the sector shoes when closed to hold the shoes closely around the axle.

DONALD D. BRYANT.
